DEVICES FOR FACILITATING BREATHING AND PRODUCING ARTIFICIAL RESPIRATION

Monroe Harry Goodner, Red Bank, N. J., assignor to Stephenson Corporation, Red Bank, N. J., a corporation of New Jersey

Application May 27, 1955, Serial No. 511,501

19 Claims. (Cl. 128—29)

This invention relates to devices for administering gas, such as oxygen, air or other gases, or a mixture of gases to facilitate breathing or for other purposes.

Such devices are attached directly or indirectly to a face mask which fits over the patient's mouth and nose or to a tracheal tube.

When the device operates to supply a relatively constant flow of oxygen, air or other gases to a patient who is capable of natural breathing, it is referred to as an inhalator. Where the device is used for aiding human beings or animals in instances where breathing is hindered or requires artificial aid or stimulation by the application alternatively of positive and negative pressures, as, for example, in cases of asphyxiation caused by drowning, poisonous gas, poliomyelitis, heart attack, or the like, it is referred to as a resuscitator.

It has been found that there is great need for a device which is sufficiently flexible in operation that it can be shifted substantially instantaneously from applying one set of alternating gas pressures to another substantially different set of gas pressures, as, for example, from approximately 14 mm. positive pressure and 11 mm. negative pressure to approximately 27 mm. positive pressure and zero negative pressure. In some cases, as, for example, when a patient's air passages have been inflamed and swollen by poisonous gases it is necessary, in order to maintain breathing, to apply intermittently positive pressure great enough to force open the patient's air passages and admit air to the patient's lungs. In such cases exhalation may be accomplished by the patient's lungs without applying negative pressure, it being desirable, however, during the exhalation period to reduce or eliminate positive pressure. In cases where it is discovered that a patient's air passages have become closed, or partly closed, it may be necessary to shift immediately from low alternate positive and negative pressures ordinarily used in artificial respiration, or from supplying a continuous flow of oxygen, air, or other gases as when the device is employed as inhalator, to supplying a higher positive pressure intermittently with periods in between for exhalation. Such greater positive pressure applications would of course be used only in extreme cases, but where it is discovered that the patient's condition demands such treatment it must be possible to supply it substantially instantaneously.

An object of the invention is to provide improved apparatus of the above described kind.

Another object is to provide a device capable of shifting efficiently and instantaneously from applying one set of gas pressures to another substantially different set of gas pressures, as for example, from approximately 14 mm. positive pressure and 11 mm. negative pressure to approximately 27 mm. positive pressure and zero negative pressure.

Another object of the invention is to provide a compact portable device which is highly flexible in operation and capable of being employed in the several ways and for the several different purposes indicated above.

2

Other objects of the invention will be apparent from the following description and accompanying drawings taken in connection with the appended claims.

In the accompanying drawings in which are shown by way of illustration several possible embodiments of my invention:

Figure 1 is a plan view of a horizontal section taken in line 1—1 of Figure 2;

Figure 2 is a side elevation of a vertical section taken in the line 2—2 of Figure 1;

Figure 3 is a fragmentary side elevational view;

Figure 4 is a top plan view of the member 14.

Figure 5 is a bottom plan view of member 14;

Figure 6 is a side elevational view taken on the line 6—6 of Figure 4;

Figure 7 is an end view of the valve closure element shown in Figures 1 and 2;

Figure 8 is a face view of a washer comprising part of the valve assembly, and

Figure 9 is a side view of the means shown in Figure 1 for adjusting the negative pressure bias.

While features of the present invention have more general application, the invention has its preferred embodiment in a relatively small, compact, portable device, which is preferably arranged for direct connection to a gas administering mask arranged for positioning over a patient's face, or nose and mouth, to administer oxygen, air, or other gas for inducing or promoting respiration, aiding breathing or other purposes. It is obvious, however, that many variations of construction can be made without departing from the invention, such as changes in shape and construction of the parts, the inclusion of a flexible hose or other coupling between the device and the mask, and the elimination of the means to convert the device into an inhalator, where such arrangement is not required.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic in their application to similar parts as the art will permit.

Referring to the drawings, the resuscitator and inhalator shown therein comprises, in general, a substantially cylindrical sheet metal casing formed of a short section of sheet metal tubing 10 and the generally rounded or dome-shaped ends 12 and 13. The end 13 has a central opening through which is inserted the tubular section 14a of the member 14 which fits within end 13 but is flatter than end 13 providing an air chamber 14b between them after they are assembled. Tubular section 14a is fitted into a tubular ferrule 15 comprising part of gas administering mask 16. Gas is supplied to the device through a gas inlet coupling assembly 11 to which is coupled a gas supply hose 18 connected to a source of regulated gas supply. The device can be of a relatively small size, for example, a resuscitator and inhalator constructed as shown in the drawings has been made having a diameter of only 2½ inches, and weighing approximately thirteen ounces.

Tubular portion 10 of the casing comprises a short piece of thin-walled tubing externally threaded at each end. While the device may be used in any position end wall 12 will be described, for convenience, as the top of the device. End wall 12 comprises a dome-shaped pressed sheet metal cap having a cylindrical internally-threaded flange 19 at its outer edge adapted to screw onto the upper end of tubular section 10. A round central opening 20 is provided in top wall 12, the portion 21 of the

wall bordering on the opening being curved inward to provide a smoothly contoured recess.

Bottom end wall 13 carries a flange 22 at its outer edge formed similarly to flange 19 to screw onto the lower end of tubular casing wall 10. The opening at the center of dome-shaped bottom wall 13 is of a relatively large diameter and projecting axially outward through it is the tubular section 14a of the member 14. Member 14 fits within member 13, leaving the air space 14b between them, and has inlet and outlet safety valves therein. Surrounding said central opening in end 13 are a plurality of apertures 13a to supply air into the space 14b. Tubular section 14a is adapted for insertion into the ferrule 15 attached to the mask 16 which may be of conventional form and construction.

A pair of diaphragms comprising an upper diaphragm 27 and a lower diaphragm 28 are clamped in horizontal position within the casing, dividing it horizontally into three chambers, namely an upper chamber 29, a middle chamber 30 and a lower chamber 31. Diaphragms 27 and 28 may be formed of any suitable flexible impervious material such as impregnated cloth, or thin corrugated metal. They are clamped on at their outer circular edges between the inwardly extending upper and lower flanges 10a and 10b of tubular casting 10, on the ring 27a, and the upwardly extending flange 14c of member 14, respectively.

A valve housing 36 is floatingly carried by diaphragm 27 and 28, the valve housing being suspended between the centers of the diaphragms. The housing is centered within the casing and prevented from turning, and thereby twisting the diaphragms, by the arms 23 and 24, pivotally connected to said housing by pivots 23a and 24a, respectively, and to the gas inlet coupling assembly by pivots 23b and 24b, respectively. Housing 36 comprises a metal casting provided with suitable gas passages and a valve chamber, which as shown is a cylinder 37 in which a slidable valve closure element 38 is carried. The valve housing 36 also carries a venturi 39 and the valve assembly 37, 38 serves to direct gas through suitable passages in the housing 36 to the venturi for purposes of supplying positive and negative gas pressures to the patient, as will be more fully described.

Diaphragm 27 and 28 each have central apertures and are each clamped in their central areas by a pair of clamping washers or discs. For example, diaphragm 27 is clamped between circular metal washers 40 and 41 which are held against the two faces of the diaphragm and which have central openings registering with the central opening in the diaphragm. Diaphragm 28 is similarly clamped between washers 42 and 43. The upper end of floating valve housing 36 has an external threaded portion 45 which extends through the central aperture provided in diaphragm 27 and clamp washers 40 and 41, and a hollow internally threaded nut 46 is screwed onto 45 thereby clamping the upper end of housing 36 in the central opening in the diaphragm. A screw 46a provided with a screw-driver slot 47 is used to close the bore in nut 46 through which access may be had to the jet 71 to clean it and venturi 39. The lower end of housing 36 carries threaded axial projection 48 which extends downward through the central aperture provided in diaphragm 28 and is clamped thereto by clamp nut 49 which is tightened against lower clamp washer 42. An internally threaded lower cap 65 is screwed onto projection 48. Cap 65 has an integral circular flange 65a which extends to within a short distance of the inside wall of tubular portion 14a of member 14 and is provided with perforations 65b so that the flange protects the inside of the casing from the entrance of foreign particles and still permits free gas passage through and around the flange. A screw-driver slot 65c on cap 65 permits ready removal for cleaning jet 72 and venturi 39.

Housing 36 is connected by a section of flexible rubber or plastic tubing 50 (Figure 1) to gas coupling assembly

11 in order to convey gas from the supply source to the floating valve housing. In addition, a valve control arm 51 comprising a straight piece of spring metal rod is rigidly supported in the casting of gas coupling assembly 11 and extends axially through gas supply tube 50 and the gas passage 52 of gas inlet nipple 53 which comprises part of valve housing 36, into cylinder 37 where the end of valve control arm 51 is received in central transverse passage 54 in valve closure element 38, so that element 38 is supported by spring arm 51 (see Fig. 7).

Valve cylinder 37 has its axis parallel to the axis of the device and hence parallel to the direction of motion of floating valve housing 36 as diaphragms 27 and 28 are flexed. Gas inlet passage 52 enters cylinder 37 in the mid-portion of its cylindrical side wall. The bottom wall of cylinder 37 is provided with an annular ridge 55 surrounding gas passage section 56a which together with sections 56b and 56c makes up a gas passage leading from the valve to chamber 57 inside cap 46. A plate 58 carrying an annular ridge 59 similar to ridge 55 is screwed into the internally-threaded upper end of valve cylinder 37 and seats against a shoulder at the lower end of the threaded section to provide a second valve seat. Plate 58 has a central opening 60 leading into a small chamber 61 above the plate which is closed by a screw cap 62 threaded into the top of the cylinder. A gas passage 63 made up of sections 63a and 63b drilled through the casting forming housing 36 extends down to lower end 48 of the casting communicating with a small chamber 64 inside lower cap 65 which is threaded onto the externally-threaded lower end 48 of the casting, as clearly seen in Figure 2.

Valve closure element 38 comprises a sliding metal block of generally rectangular shape having annular ridges 66 and 67 on its upper and lower faces opposing ridges 59 and 55, respectively, at the ends of the cylinder. The diameter of ridges 59 and 66 is made larger than the diameter of ridges 55 and 67 to require greater force to unseat member 38 from 59 than from 55 to cause the device to provide greater positive gas pressure for inhalation than negative gas pressure for exhalation. As seen most clearly in Figure 7 the four corners of block 38 are rounded off to provide cylindrical bearing portions which can slide on the inside cylindrical wall of cylinder 37 while still permitting gas to freely pass around the element 38 from gas inlet passage 52. Element 38 is drilled with a central transverse passage 54 which is of reduced diameter at its mid-portion to form a loose socket into which the end of valve control arm 51 extends as seen in Figure 7.

Interposed between element 38 and stationary valve seat ridges 59 and 55 are a pair of flexible washers 69 and 70 having a generally rectangular shape with the corners cut off to provide cylindrical bearing surfaces 55 engaging the inside wall of cylinder 37 as shown in Figure 8. It will be evident that valve closure element 38 is suspended on control arm 51 in a relatively stationary position so that as floating valve housing 36 moves up and down in response to motion of diaphragms 27 and 28 element 38 will be shifted into contact with one or the other of washers 69 and 70, these washers in turn being held against ridges 59 and 55 to cut off the gas flow through one or the other of passages 63 and 56. Valve control arm 51 is sufficiently resilient, however, to permit it to yield slightly so that, as long as the gas pressure in cylinder 37 exceeds that in the passage which is closed by element 38 by an amount sufficient to overcome the restoring force of spring arm 51, the valve will remain closed. However, when the movement of housing 36 has been sufficient to build up a restoring force equal to the gas pressure the valve will suddenly be snapped from one end of the cylinder to the other, thereby to open one passage and close the other.

Casting 36 comprising the valve housing is drilled along one side to provide a venturi passage 39 having one end

opening into the middle chamber 30 between diaphragms 27 and 28, and the other end opening into gas administering chamber 31 beneath diaphragm 28. Holes are also drilled in casting 36 from both the upper and lower ends in alignment with the venturi passage and a pair of tubes 71 and 72 are affixed in these holes to provide jet passages of the required diameter extending from chambers 57 and 64, respectively. The material of casting 36 is cut away in a smoothly rounded manner at the ends of venturi 39 to deflect gases issuing from the venturi while still permitting either of jet tubes 71 and 72 to project a jet of gas into the venturi on the opposite cycle.

Upper chamber 29 is open to the atmosphere by virtue of the space between central opening 20 and cap 46 and the presence of additional vent holes 74 in end wall member 12. Lower chamber 31 is normally closed and in communication only with the face mask 16 but is provided with safety inlet and outlet valves 25 and 26, respectively, which when unseated communicate through dish-shaped member 14 with the space 14b between it and casing end member 13. Member 14 has therein two circular openings 25a and 26a. Opening 25a is ordinarily closed by the circular valve member 25b which seats on the inner surface of member 14 and is supported at one end of spring arm 25c, the other end of which is fixed to the inner face of member 14. When the pressure within the operating chamber defined by diaphragm 28 and member 14 is reduced beyond a predetermined amount, valve 25 will open to admit air into the operating chamber to be supplied to the patient. Opening 26a is ordinarily closed by the circular valve member 26b which seats on the outer surface of member 14 and is supported on one end of spring arm 26c, the other end of which is fixed to the outer surface of said member 14. Ordinarily valve member 26 will remain closed, but it will open when the pressure within said chamber becomes greater than a predetermined amount to exhaust gases from said chamber and thereby reduce the pressure therein and in said face mask. (See Figures 2 and 4.)

Because of the air space between member 14 and end wall 13, both said intake and exhaust valves are protected from contact with external objects and from being inadvertently closed or held down, as, for example, by the thumb or fingers of a person holding the device. The vents 13a in member 13 provide a supply of air into space 14b at all times for it is impossible for all of these openings to be simultaneously closed inadvertently by the position of the thumb or fingers of the person holding the device.

An adjustable gas vent is provided in wall 10 of middle chamber 30 comprising a slot 75 cut part way around wall 10, and a threaded ring 76 which is threaded onto the upper threaded portion of cylindrical wall 10 below flange 19 of the top wall. Ring 76 is provided with a slot 77 corresponding to slot 75 in the casing wall and the outer surface of the ring is knurled to permit the ring to be turned manually to bring slot 77 into register with slot 75 to a greater or lesser extent. A short pin 78 extends in from ring 76 through slot 75 to limit the rotation of the ring to a few degrees in either direction. When ring 76 is turned to one extreme, slot 75 will be closed by the ring while at the other extreme a passage for the entrance and exit of air or other gases is provided by the aligned slots 75 and 77.

A one-way valve 79 is also provided in the wall of chamber 30 and comprises a hollow screw 80 having a gas passage 81 extending through its stem, and the cross passage 82 to prevent the valve failing if disc 84 becomes lodged across the inner end of screw 80. Screw 80 passes inward through wall 10 into a small valve chamber 83 containing a rectangular valve disc 84 of mica or other light sheet material which seats against an annular ridge 85 surrounding an opening leading from the valve chamber into chamber 30. When the gas pressure outside chamber 30 exceeds the pressure inside, disc 84 will be

pressed against ridge 85 to close the valve and prevent entrance of air through the valve. However, when the gas pressure inside the chamber exceeds that outside, disc 84 will be moved away from the ridge to permit air to pass out through chamber 83 and gas passage 81. Thus air can find access to the chamber 30 only through aligned slots 75 and 77, but gas can leave the chamber through the aligned slots and also through valve 79.

Interposed between the casing 10 and the housing 36 is a friction member 87 (Figure 1) which by its frictional drag on the housing modifies the gas pressures required to flex the diaphragm 28 and therefore the pressures which will be exerted in the operating chamber 31 and from there communicated to the patient through the tubular section 14a of member 14 and face mask 16. As shown herein, the friction member 87 is a curved leaf spring which is pivotally mounted at one end on screw 24b projecting from the casing wall, specifically coupling 11 and at the other end on screw 24a which projects from the boss 36a on housing 36. Arm 24 is also mounted on said screws and acts as a retainer to hold member 87 against the coupling 11 and housing 36. Extending through arm 24 into contact with member 87 is the adjusting screw 88 by which the extent of frictional contact of member 87 on housing 36 may be controlled.

Also extending from the casing wall is a spring member 89 which is substantially U-shaped and comprises upper and lower arms 89a and 89b which press on the housing 36 in opposite directions. As shown, the ends 30 of said spring member are secured to, and movable with, the ring 90 which is rotatable around chamber 83, i. e. around an axis which is at right angles to the axis of the housing 36, to increase the biasing force exerted on the housing in one direction and to correspondingly decrease 35 the biasing force exerted on the housing in the opposite direction. This second spring 89 is thus a second frictional member which is employed in combination with said first spring member 87 to regulate the positive and negative gas pressures relative to one another. By this 40 means adjustment of the positive pressure applied to the operating chamber and face mask can be readily varied a few degrees from a given positive pressure such as, for example, 14 mm. and the negative pressure can be varied from a given negative pressure, such as, for example, 45 11 mm.

For shifting instantaneously between two sets of gas pressures having a greater differential, for example, 27 mm. positive pressure and zero negative pressure, a third and larger leaf spring 91 is provided, together with toggle switch means 94 for moving said spring from operative to inoperative position. Said spring 91 may be either integral with or secured to a bearing block 93 which is pivotally mounted on a tubular spacing member 93a supported by said screw 24b between its head and said arm 24, for movement toward and away from the housing 36 around screw 24b. It is normally positioned to press on the housing 36 as, for example, by contact with the arm 24, to bias the housing to greatly increase the amount of gas pressure necessary to move the diaphragm 28 in the direction which controls the supply of positive pressure to the operating chamber and the face mask. By suitable adjustment of screw 24b the additional bias provided by member 91 for increasing the positive gas pressure may be made just sufficient to offset atmospheric pressure in the locality where the device is used and thereby cause the negative pressure developed during alternate movements of the diaphragm 28 and housing to be substantially zero.

The toggle switch 94 comprises the thumb piece 94a which is external to the casing, the intermediate narrow shank portion 94b comprising a ball which seats within a socket within the casing wall, and the bifurcated portion 94c extending into the casing. Between the arms of portion 94c is a pin 95 which serves as a stop against which 70 75 rides the spring 96 which is secured to the casing 10 at

96a and gives the toggle a snap action as pin **95** passes the high point of its curved path where thumb piece **94** is raised or lowered. Inwardly projecting portion **94c** extends under the free end of said spring member **91** and when in one position leaves the spring **91** free to press upon the housing **36**, through arm **24**, and when in its other position engages and lifts it out of contact with the housing. Thus, when the toggle switch **94** is in one position the device will operate at the set of pressures ordinarily employed for resuscitation, such as, for example, 14 mm. positive pressure and 11 mm. negative pressure, and when the toggle switch is moved to its other position the device will immediately operate on a substantially different set of pressures, such as for example, approximately 27 mm. positive pressure and zero negative pressure. Pressure in the order of 27 mm. positive and 0 to 3 or 4 mm. negative are desired in such cases where the patient's air passages have become substantially closed, due to swelling or presence of mucus or foreign matter, and it is necessary, at least momentarily, to supply gas under pressure much greater than the usual pressure employed in resuscitation in order to open the air passages and get oxygen into the patient's lungs.

Since no novelty is claimed herein for the gas coupling assembly, only a brief description of it is given. It comprises a metal casting **97** mounted against the inside of cylindrical wall **10** in middle chamber **30** and having a threaded nipple **98** extending out through an accommodating opening in wall **10**. The casting is clamped in the opening by a nut **99** threaded onto nipple **98** and bearing against a washer **100** shaped to conform to the outer surface of wall **11**. A cylindrical passage **101** extends through nipple **98** and terminates in a closed recess. Casting **97** has a side arm **102** carrying a branch passage **103** communicating with cylindrical passage **101**, and the end of side arm **102** carries a nipple **104** directed toward nipple **53** on floating valve housing **36**. Flexible tube **50** is fitted over nipples **53** and **104** thereby providing a continuous gas passage to valve chamber **37** from the outside of the device through gas coupling assembly **17** and tube **50**. Valve control arm **51** extends through the gas passage of nipple **104** to the intersection with gas passage **103** and is supported at its fixed end **105** in a hole drilled through the wall of arm **102** by a press-fit or by brazing, thereby affording a rigid support for the fixed end of arm **51**.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. A resuscitator comprising a casing, a pair of spaced flexible diaphragms dividing the interior of said casing into three chambers, a floating valve housing suspended by said diaphragms, means for centering the valve housing within the casing and preventing it from being displaced angularly, a valve chamber within said housing, the axis of said valve chamber being parallel to the axis of said diaphragms, a gas inlet coupling extending into said casing between said diaphragms, and a flexible gas conduit within said casing connecting said inlet coupling to said valve chamber, said floating housing carrying a pair of gas passages communicating with the respective ends of said valve chamber, a valve closure element slideable in said valve chamber, and a supporting arm therefor fixed at its outer end and extending from the casing wall into said valve chamber substantially normal to the valve chamber whereby axial movement of said floating valve housing

will shift said valve closure element between the ends of said valve chamber, alternatively to close said respective gas passages, said valve housing including a venturi passage extending between the middle one of said three chambers and a second of said chambers, and a first venturi jet fed by one of said gas passages which is closed by movement of said valve housing in a direction away from said second chamber, and a second venturi jet fed by the other of said gas passages, said first venturi jet being directed into said venturi passage to drive gas from said middle chamber and said second jet being directed into said venturi passage to drive gas from said second chamber into said middle chamber, a gas administering conduit extending from said second chamber, said casing having an atmospheric opening into the third of said chambers, and a gas escape valve leading out of said middle chamber.

2. The device claimed in claim 1, including means for regulating the total gas pressure, both positive and negative, applied to said gas administering conduit during a cycle of operation.

3. The device claimed in claim 1, including means for regulating the gas pressure within said gas administering conduit while gas is being supplied into said conduit, and compensating means for regulating the gas pressure within said conduit while gas is being exhausted from said conduit in relation to the said pressure while gas is being supplied into the conduit.

4. The device claimed in claim 1, including means for regulating the gas pressure within said gas administering conduit while gas is being supplied into said conduit, in relation to the total positive and negative gas pressure applied during an inhalation-exhalation cycle.

5. The device claimed in claim 1, including means for regulating the gas pressure applied to promote exhalation to the total positive and negative gas pressures applied during an exhalation-inhalation cycle.

6. The device claimed in claim 1, including means for regulating the total positive plus negative pressures applied during an operating cycle and means for regulating the negative pressure applied during part of the cycle relative to the total negative plus positive pressures employed during a full cycle.

7. The device claimed in claim 1, including means for shifting instantaneously from one set of positive-negative pressures to another.

8. The device claimed in claim 1, including means for loading said housing member, and means for adjusting said member to control the force it exerts on said housing.

9. The device claimed in claim 1, including means for acting on said housing to bias it and change its resistance to movement and thereby vary the pressures required to move it and consequently the positive and negative pressures applied to said gas administering conduit, and means for substantially instantaneously activating and de-activating said biasing means to shift from one of said sets of pressures to another.

10. The device claimed in claim 1, including means for biasing the housing and means for connecting said biasing means to the housing, and disconnecting it from the housing, to change the gas pressures employed from a positive pressure of substantially 12-16 mm. of mercury and a negative pressure of substantially 9-13 mm. of mercury, to a positive pressure of substantially 25-29 mm. of mercury and a negative pressure of substantially zero.

11. The device claimed in claim 1, in which said casing comprises an annular end member and in which said second chamber comprises one of said diaphragms and a member which fits within said end member and has a tubular portion which extends through the opening in the end member, said member being spaced from said end member providing a space between them, and said end member being provided with a number of vents communicating between said space and the surrounding atmosphere, and valve means in the wall of said member, com-

municating between said second chamber and said space.

12. The device claimed in claim 1, in which communication, between said first jet and the said gas passage which is closed by movement of said valve housing in a direction away from said second chamber, is provided by an axially bored nut fitting over the proximate ends of said jet passage and said gas passage, with its bore aligned with said jet passage, and a screw for closing said bore.

13. The device claimed in claim 2 in which the means for regulating the total gas pressure applied during a cycle comprises a friction member supported from the casing and bearing on said valve housing, and means for increasing and decreasing the force exerted on the housing by said member.

14. The device claimed in claim 3 in which the means for regulating the gas pressure exerted in said administering conduit during exhalation comprises means supported from the casing and extending into contact with the valve housing and adjustable toward and away from the housing.

15. The device claimed in claim 14 in which said pressure regulating means is mounted in movable support means on the inside of said casing and a slot is provided in the casing wall through which means may be inserted for moving said support means to thereby vary the force exerted by said pressure regulating means on said valve housing.

16. A resuscitator device comprising an inlet conduit adapted to be connected to a source of gas supply, venturi means including first and second jets for creating positive and negative gas pressures respectively, a distributing valve housing having a valve chamber fed by said inlet conduit and having first and second jet supply passages leading to said first and second jets, respectively, and a valve element movable between two positions in said valve chamber for alternatively closing said jet passages, the gas pressure in said valve chamber resisting the opening of the closed valve passage in both positions of said valve element, a gas chamber supplied with positive and negative gas pressures by said venturi means, one of the walls of said chamber being movable, said valve housing being coupled thereto for control thereby, and a resilient support arm for said valve element mounted independently of said valve housing, to shift said valve element from the first to the second of said positions responsive to negative gas pressure in said gas chamber and from the second to the first of said positions responsive to positive gas pressure in said gas chamber, means for varying the positive pressure and the negative pressure required to move said valve element, and means for changing the ratio between the required positive pressure and the required negative pressure.

17. A resuscitator comprising, in combination, a hollow casing having a gas administering chamber therein,

a flexible diaphragm in said casing comprising a wall of said chamber, a valve housing carried by said diaphragm and having a valve chamber therein, a flexible gas supply conduit leading into said valve chamber, a gas injector jet directed into said gas administering chamber and a gas ejector jet directed out of said chamber, said valve housing having first and second gas passages leading from said valve chamber to said jets, respectively, and a shiftable valve closure element in said valve chamber movable with respect to said valve chamber between a first position for closing said first passage and a second position for closing said second passage, a support for said valve closure element mounted in said casing independently of said diaphragm, whereby movement of said valve housing by said diaphragm will shift said closure element, means acting when in contact with said housing to bias said housing and thereby increase the pressure required to move said diaphragm in either direction, and toggle switch means for moving 20 said biasing means between active and inactive position.

18. A resuscitator comprising, in combination, a first gas chamber, a second gas chamber having a gas administering conduit leading therefrom, a venturi extending from said first to said second gas chamber, a first jet 25 in said first chamber for projecting a gas into said venturi, a second jet in said second chamber for projecting a gas into said venturi, a valve for supplying a gas alternatively to said first and second jets, said first chamber having a gas inlet and outlet passage communicating 30 with the atmosphere and an adjustable valve for regulating the rate of gas flow through said passage, thereby to control the rate of gas flow through said venturi, and means for regulating the resistance of said diaphragm to movement and the positive and negative pressures 35 required to move it.

19. A gas administering device for administering a mixture of gases, comprising, in combination, a first gas chamber, a second gas chamber having a gas administering conduit leading therefrom, a diaphragm separating 40 said chambers, a venturi extending from said first to said second gas chamber, a jet in said first chamber for projecting a first gas into said venturi, said first chamber having a gas inlet passage for admitting a second gas thereto, and an adjustable valve for regulating the rate 45 of gas admission through said inlet, thereby to regulate both the rate of gas flow and the composition of the gas mixture passing through the venturi, and means for regulating the resistance of said diaphragm to movement to provide a choice between a plurality of sets of pressures 50 within said gas administering conduit.
